CLAIM

The ornamental design for a food tray, as shown and described.

DESCRIPTION

FIG. 1 is a top-front-left perspective view of a food tray showing our new design;

FIG. 2 is a bottom-rear-right perspective view thereof; FIG. 3 is a front elevational view of the present invention, the rear elevational view being a mirror image thereof; FIG. 4 is a left-side elevational view of the present invention, the right-side elevational view being a mirror image thereof;

FIG. 5 is a top plan view thereof; and,

FIG. 6 is a bottom plan view thereof.

The broken line showing a plurality of fastener holes in FIG. 1 through 6; and a plurality of indented handle hafts in FIG. 1 through 6 is included for the purpose of showing environmental structure and forms no part of the claimed design.
